CLAIM

The ornamental design for a ceiling support for exhibition construction system, as shown and described.

DESCRIPTION

FIG. 1 is a fragmented front perspective view of a ceiling support for exhibition construction system, showing our new design;

FIG. 2 is a fragmented enlarged top plan view thereof;

FIG. 3 is a fragmented enlarged bottom plan view thereof;

FIG. 4 is a fragmented enlarged right side elevational view thereof;

FIG. 5 is a fragmented enlarged left side elevational view thereof;

FIG. 6 is a fragmented enlarged front elevational view thereof; and,

FIG. 7 is a fragmented enlarged rear elevational view thereof.

The ceiling support for exhibition construction system is shown fragmented on the end and broken away in the center to indicate indeterminate length.
